UNITED STATES PATENT OFFICE.

HENRY CLAY JOHNSON, OF MEADVILLE, PENNSYLVANIA.

APPARATUS FOR EXTINGUISHING FIRES.

SPECIFICATION forming part of Letters Patent No. 352,192, dated November 9, 1886.

Application filed June 12, 1886. Serial No. 205,000. (No model.)

To all whom it may concern:

Be it known that I, HENRY CLAY JOHNSON, of Meadville, in the county of Crawford and State of Pennsylvania, have invented certain 5 new and useful Improvements in Apparatus for Extinguishing Fires, of which the following is a specification.

My invention has reference to the protection of vessels and other structures against fire, but 10 is more especially intended for sea-going vessels.

The invention consists in the combination, with a vessel or building, of a gas-holder provided with two outlets, one controlled by a 15 thermally-operated seal and the other controlled by a manually-operated valve, a flexible pipe or hose connected with the latter, and a fan or air-forcing device, as hereinafter set forth and claimed.

20 In the annexed drawings, Figure 1 is a longitudinal vertical section through a vessel provided with my apparatus; Fig. 2, an enlarged sectional view of the gas-holders shown in Fig. 1, and Fig. 3 a similar view showing the gas-holder provided with a thermal valve in lieu 25 of the fusible plug.

A indicates the hull or body of a vessel, which may be of any type, and B B gas-holders, designed to be charged with carbonic-acid 30 gas compressed to a state of liquefaction. Each holder B is furnished with two outlet-openings, a and b, the former sealed by a thermal valve, as shown in Fig. 3, or by a cap or plug, C, of fusible metal or alloy, as shown in Fig. 2, having 35 a comparatively low fusion-point, so low that in case of fire within a short distance of the receiver the heat would be sufficient to melt the cap or plug and liberate the gas. Such fusible alloys are common and well known, and 40 therefore need not be further specified than to say that they usually consist of lead, tin, and bismuth in proportions suited to the particular use contemplated.

The gas-holders may be located at any desired 45 point or points; but it is advisable to distribute them generally over the vessel or other structure, because of the greater certainty of fusion of the plugs or caps or the greater convenience of access when it is desired to open 50 the outlets manually. As those fires which begin in the hold are most difficult of access

and control, I deem it important to place one or more of the holders B therein, providing the same with a fusible plug or cap, C, and with a valve, D, the stem or operating-rod e 55 of which may be carried to any desired point in the vessel, so that the valve may be operated without descending to the hold. In the present instance the rod e is shown carried to the main deck. Gas-holders are also shown at 60 various other points about the vessel, and it is intended to provide them in such number and size that their contents shall be sufficient to completely fill the vessel. Owing to the greater specific gravity of carbonic acid gas as 65 compared with air, it naturally seeks the lowest point in the vessel or other structure, and therefore it is not essential to place gas-holders in the hold, though I deem it advisable to do so. 70

E indicates a flexible pipe or hose connected by suitable coupling to the valve D, and serving to convey the gas from the holder to any desired point, thus enabling the fireman or attendant to direct the gas to that point in a 75 cargo or stock where it is most needed and extinguishing the fire before it can spread.

In case the fire cannot be reached, it is only necessary to batten down the hatches of that 80 part of the vessel or close the doors or windows of that portion of a building in which the fire occurs and permit the gas to escape therein until the space or chamber is filled to or above the level of the fire, which will be promptly put out when such level is reached. 85

Carbonic-acid gas being fatal to life as well as to combustion, if inhaled to any considerable extent or for a considerable time, it is important to provide means for rapidly removing it from the space into which it is permitted to escape. I therefore provide a suction-fan, F, (one or more,) or it may be any other well-known device for producing an air-current, such as a steam-jet apparatus or ejector opening from the chamber to the outer atmosphere, and either connected with the machinery of the vessel or structure or with a special engine for the purpose, or adapted to be operated manually, as the case may be. In practice I prefer to place one or more gas-holders 95 on each covered deck of the vessel and in the hold; or in case of a building, one or more on 100

each floor, and to provide a corresponding number of fans or ejectors similarly arranged.

With the hose or pipe E and valve D, I am enabled to utilize the gas for cooling purposes, 5 the escaping gas rapidly expanding to its original volume, and in doing so taking up the heat of the surrounding atmosphere and producing intense cold. For the practical carrying out of this part of the plan it is essential to employ an expansion pipe or coil, in order to provide a large cooling surface and to bring the gas close to all parts of such surface. Practical tests have demonstrated that good rubber

hose answers almost as well for this purpose as 15 does metal pipe, and as it possesses the advantage of flexibility and consequent adaptability to be carried about to any desired point I prefer to use it instead of metal pipe.

The gas-holders should be made portable, in 20 order that when empty they may be readily removed and recharged, or replaced by others duly charged, and for this reason, among others, I employ suitable couplings for connecting and disconnecting the hose.

25 I do not claim herein, broadly, the use of carbonic-acid gas as a means of extinguishing fire, nor, broadly, a gas-holder provided with

a fusible plug, as I have hitherto embraced these ideas in other patents.

The thermal valve illustrated in Fig. 3, which 30 I consider the equivalent of a fusible plug or seal, may be of any desired construction, a very simple plan being illustrated in Fig. 3. As shown in said figure, the expansion of the vertical stem or rod allows an opening in the 35 latter to register with an opening in the top of the holder B, and allows the escape of the gas or air.

Having thus described my invention, what I 40 claim is—

In combination with a vessel or building, a gas-holder provided with two outlets, a seal applied to one of said outlets and adapted to open the same at a predetermined temperature, a valve applied to the other, a flexible pipe or 45 hose connected with the valve, and a fan or air-forcing device connecting with the chamber which receives the gas escaping from the gas-holder, all substantially as set forth.

HENRY CLAY JOHNSON.
